ROTATIONAL MOLDING INSTRUCTION DEVICE

Francis Paul Pracilio, 966 Grant Ave.,
Pelham Manor, N.Y. 10803

Filed July 28, 1972, Ser. No. 276,140

Term of patent 14 years

Int. Cl. D15—09

U.S. Cl. D54—8

FIG. 1.

FIG. 2.

FIG. 3.

FIG. 1 is a perspective view of a rotational molding instruction device showing my new design;

FIG. 2 is a perspective view looking from the other side thereof with a portion broken away for convenience of illustration; and

FIG. 3 is a perspective view looking from the rear thereof.

I claim:

The ornamental design for a rotational molding instruction device, substantially as shown and described.
